UNITED STATES PATENT OFFICE.

WILLIAM R. HARGIS AND HENRY W. LINDENMUTH, OF HARRISBURG, ILLINOIS.

ALARM APPARATUS.

1,277,917.

Specification of Letters Patent. Patented Sept. 3, 1918.

Application filed July 7, 1916. Serial No. 107,988.

To all whom it may concern:

Be it known that we, WILLIAM R. HARGIS and HENRY W. LINDENMUTH, citizens of the United States, residing at Harrisburg, in the county of Saline, State of Illinois, have invented a new and useful Alarm Apparatus, of which the following is a specification.

The present invention appertains to alarms, and aims to provide novel and improved alarm apparatus adapted for use in banks, jewelry stores, and in other public or private places, whereby an alarm signal is given at a police station, fire department, or the like, for calling help in case of a hold up, fire or similar circumstance.

The present apparatus is adapted especially for use as a burglar alarm, although it can be used as a fire alarm or for kindred purposes, and is adapted especially for use in banks, jewelry stores, and the like, in order that when a hold up occurs, the proprietor or employee can at various points of the office or room turn in an alarm call at the police station or the like, without creating suspicion, whereby a call for assistance is made without the knowledge of the burglar, in order that he may be intercepted.

The apparatus is so operable, that a signal will be given in the event that the main conductors are cut or broken during or previous to the hold up, as by a maliciously inclined person, so that even if a signal can not be given from the bank, jewelry store, or the like, a signal will be given by the cutting or breaking of one of the main conductors, the alarm being operated electrically.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a diagrammatical view of the apparatus.

Fig. 2 is an edge view of the switch device.

Fig. 3 is a detail view illustrating the pointer of said device.

The apparatus includes a battery or other suitable source of electrical energy 18' located in the bank, store, or the like, and having its opposite poles connected by line conductors 15' and 16' with the terminals of the electromagnet 17' of a relay located in the police station, or the like. If desired, instead of using one of the line wires 15'—16', one pole of the battery 18' and one terminal of the magnet 17' can be grounded to complete the circuit by way of ground. The switch 2' located in the bank, or the like, is connected to the conductors 15'—16' whereby when the switch is closed, a cross will be provided in the circuit to short circuit the relay, in order that the relay switch which is normally energized will be deenergized. Said relay will also be deenergized should the line conductors or wires be cut, thus assuring of the deenergization of the relay magnet 17' in the event that the switch is closed, or the circuit broken or crossed in any manner whatever. The magnet 17' normally attracts an armature switch 19' 80 away from an adjustable screw contact 20' which is connected by means of a conductor 25' with one pole of a battery or other source of electrical energy 22' and one terminal of an electric bell 24' or other audible signal device. The armature switch 19' is connected by a conductor 21' with an electromagnet 27' applied to and carried by a metallic plate 40 preferably disposed in an upright position. The other pole of the 90 battery 22' is connected by a conductor 31' with the plate 40, and the bell 24' is connected by a conductor 23' with a spring contact 32^a attached to and insulated from the plate 40. A second spring contact 32' 95 is attached and insulated from the plate 40, and is connected to the electromagnet 27'. A spring tension armature 30' is carried by the plate 40 in a depending position to be attracted by the electromagnet 27', and is provided at its lower end with a hook or catch 36'. A spindle 41 is journaled for rotation through the plate 40 below the magnet 27' and above the contact 32^a, and has attached thereto a radial switch blade 105 42, the free end of which is swingable between and engageable with the contacts 32' and 32^a. When the blade 42 is raised in horizontal position with its free end engaging the contact 32', an outstanding pin or lug 43 of the blade 42 is engageable with the hook or catch 36' to hold said blade in

raised position, and when the armature 30' is attracted by the electromagnet 27', the catch 36' is removed from the lug 43, thus enabling the blade 42 to swing downwardly 5 to a depending position in engagement with the contact 32^a. To assist the movement of the blade 42 from the contact 32' into engagement with the contact 32^a, a spring 44 connects the plate 40 and spindle 41 and 10 tends to rotate said blade as indicated. The electromagnet 27', armature 30', contacts 32'-32^a and blade 42 are preferably located upon one side of the plate 40, and a pointer 45 is located upon the other side of the plate 15 and is attached to the respective end of the spindle 41. This pointer 45 serves as an indicator, and can be exposed to view whereby a visual signal is given when the blade 42 is in either position, the pointer 45 swinging 20 in the same direction as the blade 42. Normally, the blade 42 is held in engagement with the contact 32' by means of the armature 30' which acts as a detent, the electromagnet 27' will therefore be connected 25 in circuit with the battery 22' and armature switch 19', but said armature switch being normally attracted by the electromagnet 17', will open the circuit. Should the circuit of magnet 17' be crossed 30 or cut at any point, or should the switch 2' be closed, the magnet 17' will at once become deenergized, thus releasing the armature switch 19' which will be swung by spring tension against the contact 20', thus 35 closing the circuit including the armature switch 19', contact 20', conductor 25', battery 22', conductor 31', plate 40, blade 42, contact 32', electromagnet 27' and conductor 21'. The armature 30' is therefore attract- 40 ed, to release the blade 42, which will then swing downwardly away from the contact 32' into engagement with the contact 32^a. The circuit of electromagnet 27' is thus

opened immediately after the armature 30' is attracted, whereby current will no longer flow through said electromagnet, but the blade 42 in engaging the contact 32^a will close the circuit including the bell 24' and battery 22', said circuit including the battery 22', bell 24', conductor 23', contact 32^a, blade 42, plate 40, and conductor 31'. Thus the entire electrical energy is used for operating the bell to produce the audible signal, in connection with the visual signal provided by the movement of the pointer 45. 55 The switch 2' illustrated diagrammatically in Fig. 1, can be taken to represent any suitable switch or contact device in the bank, office, or the like, for providing a short circuit. 60

Having thus described the invention, what is claimed as new is:

A device of the character described embodying a plate, an electromagnet secured to the plate, a pair of contacts carried by the plate, a spindle journaled in the plate, a switch arm secured to and extending radially in one direction from the spindle, means normally forcing the switch arm toward one contact, a spring tension hook adjacent the second contact and adapted to be swung by the electromagnet when the magnet is energized, a lug projecting from the face of the switch arm and engageable with the hook to normally hold the switch arm in engagement with the second contact, and an indicator carried by the spindle. 75

In testimony that we claim the foregoing as our own we have hereto affixed our signatures in the presence of two witnesses.

WILLIAM R. HARGIS.
HENRY W. LINDENMUTH.
